This invention relates to a concrete reinforcing bar of 10 hexagonal cross-section.

In building, and particularly in engineering structures, there are increasing requirements for heavy structures of reinforced concrete which are widely spanned and/or heavily loaded. The erection of such structures makes necessary the use of reinforcement of great bearing capacity capable of supporting high tensile or compression stresses guaranteeing full safety also in thick bars.

Of course, reinforcements from thick smooth round bars stressed at high tensions would lead to excessive cracks on beams or tie rods. Such cracks facilitate the access of humidity, water and/or other damaging elements to the reinforcements, thus causing their rusting and in extreme cases, the collapse of the whole structure. Therefore, the recent regulations of advanced countries limit the crack widths at 0.1 mm. up to 0.3 mm., depending on the function of the structures involved.

Since the crack width represents the decisive criterion for the safety of reinforced concrete structures, prominent experts carried out extensive systematic research in order to develop formulas for determining the crack width. This diminishes, when the bond between reinforcing bars and concrete increases. In this respect, several shapes were given to reinforcing bars, nevertheless, they do not satisfy the main requirement of the theory of reinforced concrete for a perfect unity of the bars with the concrete.

Thus, a reinforcing bar having the cross-section of a six-pointed star with transverse ribs, the flanks of which decline at 30° from the sides of the circumscribed hexagon, is known as one of the best. However, during industrial production, this angle was reduced by wearing of the channels and the deepness of the alveoli became insufficient to guarantee the required bond strength. Therefore, it was necessary to change the channels often and to interrupt the rolling two or three times during a shift. These costly channels with many transverse incisions were often elaborated upon, thus the consumption on rollers was excessive. Moreover, the transverse ribs reduce the strength of such bars under many repeated loads of bridges and similar structures.

The present invention is directed to a concrete reinforcing bar of a cross-section and of such surface shapes which guarantees the above-mentioned perfect unity with concrete, thus reducing the crack widths on the allowable measures, which facilitates manufacturing and regular bending of the bar.

The bar consists essentially of four pair of flanks which are symmetrical to one of the longest symmetrical axes S—S and decline from the sides of the circumscribing hexagon at more than 30°, and from the remaining two pair of symmetrical flanks which are nearly perpendicular to the axis S—S declining from the sides of hexagon at nearly 30°. As a result, this bar has six basic deep grooves which are divided in deep, narrow and short alveoli by closely spaced transverse or diagonal ribs, flat with the side of the circumscribing hexagon.

The angles over 30° between the flanks and the hexagon sides permit turning the grooves on rollers with two tools having one cutting edge or by means of a single tool with two edges without damaging the adjacent longitudinal ribs of the channel.

The diagonal ribs are advantageous for structures which

2

are susceptible of repeated dynamical loadings. The transverse forces caused by the inclination of the diagonal ribs are absorbed by the neighboring longitudinal ribs. Thus, there will be eliminated the splitting of concrete existing when pulling of other types of bars with extending transverse ribs and particularly diagonal ribs.

It is also possible to mark one quality steel by means of transverse ribs, another quality steel by means of ribs inclined to the left and a third quality steel by means of ribs inclined to the right as shown in FIGURE 3 of the drawings. Such a clear marking is of great practical importance for the safety of structures, as it eliminates any mistakes of the steel quality in mills, on stocks, on plots, as well as in structures, even after a long period of installation. The flat transverse or diagonal ribs of these bars when bent, eliminate the concentrated pressures on them from the pin which presses uniformly on their longitudinal ribs. Thus, fragility is also eliminated. Also, the pulling of the bars from stocks and the bending thereof is facilitated.

The bar according to this application can also be shaped in a different manner.

When the bar is thick, the alveoli would become too wide and the transverse ribs too thick; thus, the gripping of the concrete in the depth of the ribs will be insufficient, and there would be an increase in the consumption of steel for transverse ribs which do not collaborate in longitudinal stresses. Therefore, it is very advantageous to insert one or more secondary longitudinal basic ribs into such wide longitudinal grooves; their external edges lie on sides of the circumscribing hexagon and their flanks are parallel to those of the closely disposed longitudinal main ribs.

The manufacturing of all of these bars is easy. Moreover, the symmetrical and regular distribution of material in each cross-section facilitates the bending of the bars, all of which is of great practical importance.

Preferred embodiments of bars made in accordance with this invention are shown in the attached drawings in which:

FIGURE 1 shows a bar, the cross section of which is a six point star with steep flanks, the longitudinal grooves being interrupted by diagonal ribs *r* inclined to left as viewed in the drawing.

FIGURE 2 shows a thick reinforcing bar of the basic cross section according to the FIGURE 1, but with two secondary longitudinal ribs in each of the six basic grooves having edges on the sides of the circumscribing hexagon. The longitudinal grooves are interrupted by transverse ribs *r*.

FIGURE 3 shows a bar, the cross section of which consists of two halves of the cross section according to the FIGURE 1 (turned at 90°), among which three pairs of trapezoids are inserted having their edges on the side of the circumscribing prolonged hexagon. The grooves are interrupted by ribs *r*, inclined to the right as viewed in the drawing.

In all of these figures the imaginary sides of circumscribing hexagon are identified as *p*, the flanks which decline from the side *p* more than at 30° as *f*, and the flanks which decline from the side *p* less than at 30° as *f'*.

I claim:

1. A longitudinally grooved concrete reinforcing bar of six-pointed star shape in cross section including two pairs of flanks symmetrical to one of the longest symmetrical axes S—S declining from the sides of the circumscribing hexagon at nearly 30°, characterized by four pairs of main flanks symmetrical to said symmetrical axis and declining at an angle greater than 30° from the sides of the hexagon, and a plurality of diagonal ribs rolled in the longitudinal grooves of the bar.

2. The reinforcing bar according to claim 1, characterized by one secondary longitudinal rib located in the

basic grooves of the bar, whereas as the edges of these ribs lie on sides of the circumscribing hexagon and their flanks have the same declination from the hexagon sides as the corresponding flanks of the basic grooves.

3. The reinforcing bar according to claim 1, characterized by a plurality of secondary longitudinal ribs located in the basic grooves of the bar, whereas the edges of these ribs lie on sides of the circumscribing hexagon and their flanks have the same declination from the hexagon sides as the corresponding flanks of the basic grooves.

4. The bar according to claim 1, characterized by one pair of adjacent trapezoids formed perpendicularly to the longer symmetrical axis S—S between the two halves of the basic cross section, whereas the edges of the trapezoids lie on the sides of the circumscribing hexagon and the flanks decline from the latter at the same degree as the corresponding flanks of the basic grooves.

5. The bar according to claim 1, characterized by a plurality of pairs of adjacent trapezoids formed perpen-

10

15

dicularly to the longer symmetrical axis S—S between the two halves of the basic cross section, whereas the edges of the trapezoids lie on the sides of the circumscribing hexagon and the flanks decline from the latter at the same degree as the corresponding flanks of the basic grooves.
